US00D331745S

United States Patent [19]

Miyake et al.

[11] Patent Number: Des. 331,745
[45] Date of Patent: ** Dec. 15, 1992

[54] COMBINED DATA INPUT AND OUTPUT TERMINAL FOR PROGRAMMABLE CONTROLLER

[75] Inventors: **Takao Miyake; Masayoshi Kawaishi; Katsuhiro Ishida; Yukio Kanaoka**, all of Nara, Japan

[73] Assignee: **Sharp Kabushiki Kaisha**, Osaka, Japan

[**] Term: **14 Years**

[21] Appl. No.: **773,304**

[22] Filed: **Oct. 9, 1991**

[30] Foreign Application Priority Data

Apr. 23, 1991 [JP] Japan 3-12119
[52] U.S. Cl. **D14/100**

[57] CLAIM

The ornamental design for a combined data input and output terminal for programmable controller, as shown and described.

DESCRIPTION

FIG. 1 is a top plan view of a combined data input and output terminal for programmable controller showing our new design;

FIG. 2 is a front elevational view thereof;

FIG. 3 is a right side elevational view thereof;

FIG. 4 is a rear elevational view thereof;

FIG. 5 is a left side elevational view thereof; and,

FIG. 6 is a bottom plan view thereof.

FIG. 1

FIG. 2

FIG. 3***FIG. 4******FIG. 5****FIG. 6*
